UNITED STATES PATENT OFFICE.

LOUIS A. CASGRAIN, OF WINCHESTER, MASSACHUSETTS, ASSIGNOR TO UNITED SHOE MACHINERY COMPANY, OF PATERSON, NEW JERSEY, AND BOSTON, MASSACHUSETTS, A CORPORATION OF NEW JERSEY.

MACHINE FOR INSERTING METALLIC FASTENINGS.

No. 898,435.

Specification of Letters Patent. Patented Sept. 15, 1908.

Application filed June 9, 1902. Serial No. 110,726.

To all whom it may concern:

Be it known that I, LOUIS A. CASGRAIN, a citizen of the United States, residing at Winchester, in the county of Middlesex and State 5 of Massachusetts, have invented an Improvement in Machines for Inserting Metallic Fastenings, of which the following description, in connection with the accompanying drawings, is a specification, like letters on the 10 drawings representing like parts.

This invention consists of improvements in machines for inserting fastenings.

My improvements are shown as applied to a well known machine of the type represented 15 by United States Patent No. 440,805, dated November 18, 1890, which machine is arranged for forming from continuous screw-threaded wire, fastenings of lengths varying according to the thickness of the stock. In 20 that machine the stock is supported on a horn, and the head of the machine which is moved laterally for feeding the stock is lifted after the feeding, that the head may be returned to its starting position, but it should 25 be understood that many features of my invention are applicable to other types of machines, and my claims should not therefore be limited to the particular form of machine herein shown. In said machine the wire 30 carrying spindle is rotated continuously at a high speed, and said spindle by a worm engaging a worm wheel on a shaft, rotates said shaft that cams thereon may actuate the various parts of the machine in the proper 35 time and order to effect the feeding of the wire longitudinally through the spindle, the cutting off of the wire in the stock to form a fastening, the feeding of the stock, and the release of the stock to permit the stock feeding mechanism to return to its starting 40 position. As said machine has heretofore been constructed, when the workman desired to stop the insertion of fastenings he operated a hand lever which arrested the operation of 45 the wire feeding mechanism, but the cam shaft with its cams and the mechanism actuated thereby continued in operation and it was also necessary for the workman to raise the head by a separate treadle in order to 50 move or apply the work.

In the machine embodying the present invention, I have arranged mechanism for stopping the rotation of the cam shaft, and hence stopping the operation of the various mech-

anisms operated by the cam shaft, without 55 stopping the rotation of the wire-carrying spindle. This mechanism also operates to leave the head in elevated position when the insertion of fastenings is stopped, so that the work can readily be removed from or applied 60 to the horn without a separate operation for raising the head. In the form of this mechanism herein shown, I have arranged for connecting the cam shaft with and disconnecting it from the wire carrying spindle. This 65 mechanism, which is controlled by means of a treadle, is arranged to stop the machine always at a predetermined point, so that the head of the machine is left in elevated position to facilitate the removal and applica- 70 tion of the work from and to the horn; so that the cam for operating the wire feeding mechanism is stopped at such a position that the proper length of wire is secured for the first 75 fastening to be made when the machine is again started, and so, also, that the knives which cut the fastenings from the wire are rendered inoperative, thereby preventing their being dulled by striking each other.

Figure 1 in side elevation shows part of a 80 machine with my invention applied thereto in one of the best forms now known to me; Fig. 2 shows a partial rear end view and section of the machine shown in Fig. 1; Fig. 3 is a detail much enlarged of part of the ma- 85 chine shown in Fig. 1; Fig. 4 is an enlarged view of part of the front end of the machine; Fig. 5 is a sectional detail showing the roller carrier or sleeve of the clutch in position be- 90 tween the shaft and the worm gear, the latter and the carrier being in longitudinal section; Fig. 6 is a section in the line x', Fig. 3, looking to the right; Fig. 7 shows one of the springs 95 14 detached; Fig. 8 is a section in the dotted line x', of Fig. 3; Fig. 9 in perspective shows the sleeve and the shoe to engage it and release the clutch from the shaft. Fig. 10 is a partial right hand side elevation of the ma- 100 chine shown in Fig. 1; Fig. 11 is a detail view showing part of the wire-cutting mechanism; Fig. 12 is an enlarged sectional detail in the line y—y, Fig. 9; and Fig. 13 is a sectional detail of part of the spindle D showing the wire-feeding mechanism.

Referring to the drawings, C represents 105 part of a hollow column adapted to stand on the floor, E a head having a stem E' that enters and is free to slide and turn in the col-

umn, and E^2 is a bracket extended from the stem through a slot in the column. The bracket receives loosely a post E^3 to which is connected the revoluble stock support A , an abutment E^4 of the column C and an adjustable collar E^5 on the post, determining the normal position of the top A' of the horn.

D represents a hollow spindle having its bearings in the head E and rotated constantly at high speed by a belt D' extended over a pulley F^2 fast on said spindle. The wire to be fed through the spindle is carried by a reel F mounted on the upper end of the spindle, and is fed intermittently by two feed rolls k each mounted on shafts k' , the opposite ends of which, see Fig. 10, have pinions k^2 that intermesh. These shafts are rotated intermittently by or through an intermediate pinion k^3 engaged by a larger pinion k^4 mounted on one end of a shaft k^5 which is provided at its other end with a ratchet-toothed wheel k^8 . Rotatably mounted on the shaft k^5 is the sleeve k^6 of a pawl carrier having the pawls k^9 adapted to engage and rotate the ratchet-toothed wheel k^8 , as shown in Fig. 1. For actuating the pawl carrier to move the feed rolls intermittently I have shown a lever K pivoted at K' . This lever at one end embraces a block m' mounted loosely on a stud m^2 extended from a slide bar m^3 the ends of which are arranged to slide in guides m^4 . The slide bar m^3 has a stud m^5 that enters a ring c^2 that embraces a nut c loosely surrounding the spindle D and having depending from it a rack bar J the teeth of which engage the pinion m mounted on the sleeve k^6 of the pawl carrier, as shown in Fig. 13. The lever K has a roller or other stud m^6 that is acted upon by the cam or actuator L mounted on the shaft I which rotates in bearings in the head E . The length of the fastening to be inserted is controlled through the usual measuring leg n connected with the rear end of the lever K . The cam L has a projection C' see Fig. 2 for imparting movement to the wire cutting mechanism shown as a lever C^2 pivoted on the head at C^3 . The lower end of the lever is inturned, as shown by dotted lines Fig. 2, and is toothed, see Fig. 10, to engage a pinion n^2 fast on a stud having at its lower end a pinion n^3 that engages teeth of two arms n^4 , n^5 , having each a cutter n^7 for severing the wire close to the surface of the stock. The shaft I has a second cam or actuator B provided with a groove d^4 for moving a lever V employed to lift the head carrying the foot plate or nose C^4 to unclamp the stock, that the head may be returned to its starting position after having been moved laterally to feed the stock. Said shaft has a third cam or actuator O for moving the head laterally to effect the feeding of the stock.

N represents a vertical rod sustained in the head E , a hollow rock shaft N^2 embracing said rod and having at its upper end an arm

N^3 carrying a roller stud to enter the groove in the cam O . A forked arm N^4 at the lower end of said hollow rock shaft embraces loosely a stud or fulcrum N^5 adjustable horizontally in an extension C^6 of the column C . The movement of the hollow rock-shaft by the cam O insures the swinging of the head E for a greater or less distance about the stem E' as a pivot, to feed the stock after the insertion of each fastening for a distance to correspond with the spacing of the fastenings.

A stand C^{2x} fixed to the column C sustains a ratchet toothed plate C^5 , and has ways to receive and guide a slide D^2 connected with the lever V by a rod d' . The slide D^2 carries a pawl D^3 which, after the stock has been fed, may engage one of the teeth of said ratchet plate, and the cam B thereafter acting on the lever V , will lift the head from the stock whatever its thickness, thereby unclamping the stock, that the head may be returned to its starting position preparatory to inserting another fastening and feeding the stock, all as more fully shown and described in United States Patent No. 440,805, November 18, 1890.

On the shaft b^4 carrying the lever V is an arm b^3 to which is jointed a controlling bar V^2 having a cast-off b . A spring e^3 acts normally to lift the arm b^3 so that a roller stud thereon may be acted upon by the periphery of the cam B . As the head arrives in its starting position after feeding the stock, the shape in the groove of the cam B is such as to let the head descend that the nose or foot piece may rest upon the top of the stock, and just at this time a projecting part of the cam B acts to depress the arm b^3 and cause the cast-off b to meet and disengage the pawl D^3 from the tooth of the ratchet plate C^5 then engaged by it, whereby the pawl is held out of engagement with the teeth of the plate C^5 until it is desired to again raise the head to feed the stock. The edge gage H is sustained by the column C .

The parts so far specifically described and referred to by letter with the exception of the wire-cutting mechanism are common to United States Patent No. 440,805, dated Nov. 18, 1890, wherein the said parts are more fully and particularly described.

I will now proceed to describe my present improvements as embodied in the machine herein shown.

I have extended the main shaft I forwardly, as represented in Figs. 1, 3 and 4 and have surrounded said shaft loosely by a hub a having a connected worm gear a' that is engaged and rotated constantly by the worm G carried by the spindle D . The gear a' has secured within it a steel ring 8 in which is inserted loosely a sleeve 12 the outer end of which has a recess a^x , to overlap the tapered end of the bearing l^x secured to the head and in which the shaft I turns. The hub a is prevented from moving endwise on the shaft I .

by an adjustable end-thrust block 2^x, as shown in Fig. 3. Supporting the gear a' and its hub, as described, on the prolonged end of shaft I insures a firm bearing for the gear and its hub.

Referring to Figs. 5, 8, 9, and 12, the sleeve 12 is provided with spaces or openings in which rollers 13 are seated and the shaft I has four flattened portions 10 on which the rollers rest when the shaft and gear a' are unclutched, as hereinafter described. The sleeve 12 surrounds the shaft I, and the hub a of the gear a' surrounds the sleeve 12, so that the rollers 13 are interposed between the outer surface of the shaft I and the inner surface of ring 8 in the hub a. The sleeve on its inner side is provided with recesses 14^x see Fig. 12 which receive the ends of springs 14, the other ends of the springs engaging seats cut in the shaft I, as shown in Fig. 8, whereby the sleeve 12 and shaft I are yieldingly held together. The springs are normally under tension, and when they are free to act they turn the sleeve about the shaft for a sufficient distance to carry the rollers off the flattened portions 10 of the shaft so that they will clutch the outer surface of the shaft and the inner surface of the ring 8 in hub a, thereby connecting the gear a' and shaft I. This mechanism constitutes one form of the well known "Horton clutch", but it will be obvious that any other usual clutch mechanism could be employed without departing from my invention. The periphery of the outer end of the sleeve 12 is cut as shown by dotted lines Figs. 6 and 9, to constitute a cam part 16 and form a shoulder 17. The column C is provided with a stand 18 having a stop 19 and a stud 20 to support a dog 21 controlled as to the extent of its movement by said stop. One end of the dog is acted upon by a rod 22 operated by a treadle or lever, not shown, located preferably at or near the floor and controlled by the workman, whereby the rod 22 may be lifted to turn the dog 21 in the direction of the arrow thereon, Fig. 4. A spring 23 connected at one end with the dog and at its other end with a stud C^s projecting from the stand 18 moves the dog in a direction opposite the arrow whenever the workman removes his foot from the treadle.

The head of the machine has a suitable stand 24 that receives a pivot pin 25 for a clutch controller shown as composed of a sleeve 26 having three arms 27, 28 and 29. The arm 29 is hollow and receives the stem 30 of a shoe 31, shown as notched, see Fig. 9, to engage with the cam surface 16 and the shoulder 17 of the end of the sleeve 12. The arm 29 contains a spring which acts normally to press the stem 30 outwardly, a stop screw 32 entering a groove in said stem preventing the same from rotating in the sleeve 65 and from being withdrawn fully therefrom.

The arm 28 is acted upon at its end by a suitable spring 33^x, see Fig. 6, that causes the arm 27 to be kept normally against the dog 21.

The stand 24 has, as shown in Fig. 6, a split ear 33 in which is clamped a toe piece 34 the position of which is determined by a screw 35. The toe piece constitutes a safety device to positively turn the arm 29 of the controller outwardly in case the rollers 13 of the clutch device should fail to release the shaft after the workman removes his foot from the treadle to stop the machine. In such case the stem 30 would be forced downwardly against the tension of the spring in hub 29 until the shoe 31 engaged the toe piece 34 when the lever would be turned to move shoe 31 out of the path of movement of shoulder 17, thus preventing any breakage of the parts.

Whenever the operator desires to begin to insert fastenings he elevates the rod 22 to turn the dog 21 and cause the clutch controller to be moved in a direction to withdraw the shoe 31 from contact with the shoulder 17 of sleeve 12, and instantly the springs 14 turn the sleeve 12, thereby moving the rollers 13 off the flattened portions 10 of the shaft I so that they will be wedged between the outer surface of said shaft and the inner surface of the ring 8 in the hub of the gear a', and connect the gear a' to the shaft I. Whenever the operator releases the rod 22, the spring 23 acts to turn the dog 21 away from the arm 27 of the controller so that the spring 33^x turns the controller to put the shoe 31 against some part of the periphery of the outer end of the sleeve 12, and before the completion of a rotation of the sleeve the shoe meets the cam surface 16, and finally engages the shoulder 17, instantly arresting the further rotation of the sleeve with the shaft, and removing the rollers from clutching or driving contact with the interior of the gear a', so that the shaft I and gear a' are unclutched in order that said gear may continue to rotate while the cam shaft I and its cams stop at a definite position, leaving the stock unclamped and the parts moved by said cams at rest in their normal or starting position.

The cam for raising the head is so arranged that when the machine stops the head is left in elevated position to allow the work to be removed from or applied to the horn without the necessity of a separate operation for raising the head, and the cam which operates the wire feeding mechanism stops in such position that when the machine is again started the lever K can be given its full movement 125 to feed enough wire for a fastening of the greatest length if so desired, the length of the fastening to be inserted being determined by the thickness of the stock.

The worm gear a' is the form of "con-

stantly moving member", referred to in the claims, which I have employed in the embodiment of my invention herein shown and described. The cams on the cam shaft I are 5 the actuators referred to in my claims which, as has been explained, are arranged to be connected with or disconnected from the constantly moving member at the will of the operator.

10. By the term "constantly moving member" employed in the claims, I intend to include and cover any constantly moving member, however operated, which member when started by the operator, continues to move 15. while the operator stops and starts at will other operative parts of the machine, and I intend to cover broadly any constantly moving member of a machine, and any suitable means coacting with it, or any means intermediate said member and an actuator or actuators whereby the actuator or actuators may be stopped independently of the constantly moving member.

I have herein shown the head having the 25. foot plate as movable from and toward the upper end of the stock-support, but as many features of my invention may be used to equal advantage in machines in which the horn is depressed to unclamp the stock, I 30 shall use in the claims the expression "to change the relative positions of the stock support and foot plate" as covering the movement of either the foot plate or the stock support to unclamp the stock, or to 35 separate them for the removal or application of stock to the stock support.

Having described my invention, what I claim and desire to secure by Letters Patent is:

40. 1. In a machine for inserting fastenings, the combination with fastening-inserting mechanism, comprising wire feeding means and a driving member, of a constantly moving member driven by said driving member, 45 an actuator for said wire feeding means in operative relationship to said moving member and means intermediate said moving member and actuator to stop said actuator and wire feeding means when in predetermined position while the moving member continues in operation.

2. In a machine for inserting fastenings, the combination with fastening-inserting mechanism comprising wire feeding means 55 and a driving member, of a constantly moving member driven by said driving member, wire cutting means, actuators for said wire feeding means and wire cutting means in operative relationship to the moving member, 60 and means intermediate said moving member and said actuators to stop said actuators and the wire feeding and wire cutting means when in predetermined position while the moving member continues in operation.

3. In a machine for inserting fastenings, 65 stock support, a head carrying a driving member, and having a foot plate to bear on the stock, a constantly moving member driven by said driving member, an actuator in operative relationship to said moving member, means moved by the actuator for moving the head to feed the stock and means intermediate said member and said actuator to stop the actuator when in predetermined position and restrain the movement of the 70 head for feeding while the moving member continues in operation.

4. In a machine for inserting fastenings, 75 a stock support, a head carrying a driving member and having a foot plate to bear on the stock, a constantly moving member driven by said driving member, an actuator in operative relationship to said moving member, means operated by said actuator to change the relative positions of the foot 80 plate and stock support to unclamp the stock between the operations of inserting fastenings, means intermediate said moving member and actuator to stop said actuator and the means operated by it when in a predetermined position for the removal of the unclamped stock while the moving member continues in operation.

5. In a machine for inserting fastenings, 85 a stock support, a head carrying a driving member and having a foot plate to bear on the stock, a constantly moving member driven by said driving member, an actuator, means operated by said actuator to change the relative positions of the foot plate and 90 stock support to unclamp the stock between the operations of inserting fastenings, a clutch co-acting with said moving member and actuator, and means to cause said clutch to release the actuator from the control of 95 said moving member while the stock is unclamped for its removal from the stock support in order that said actuator and the means operated thereby may remain at rest 100 while said member continues in operation.

6. In a machine for inserting fastenings, a continuously moving wire carrying spindle, 105 wire feeding means carried thereby, an actuator for moving said wire feeding means, and manually controlled means intermediate said spindle and actuator to stop the actuator and the wire feeding means when in predetermined position while the spindle continues to rotate.

7. In a machine for inserting fastenings, a 110 wire carrying spindle having a worm, means to rotate the spindle continuously, wire feeding means, an actuator for moving said wire feeding means, a worm gear moved by said worm, a clutch intermediate said worm gear 115 and actuator, and means to move said clutch that the actuator and wire feeding means 120 may be left at rest in predetermined position

- while the worm gear and spindle continue in operation.
8. In a machine for inserting fastenings, a stock support, a head having a foot plate to bear on the stock and clamp it against the stock support, an actuator, means operated by said actuator to lift the head from the stock whatever its thickness to unclamp the stock, a moving member, means between said moving member and actuator to stop the actuator when the head is lifted and at rest for the removal of the stock from the stock support while the moving member continues in operation.
- 15 9. In a machine for inserting fastenings, a stock support, a head having a foot plate to bear on the stock and clamp it against the stock support, an actuator, means operated by said actuator to lift the head from the stock whatever its thickness to unclamp the stock, a moving member; means between said moving member and actuator to stop the actuator and the means operated by it, when the head and foot plate are lifted with the stock unclamped for removal from the stock support while the moving member continues in operation, and means to thereafter cause said moving member to pick up and start said actuator and the means operated thereby to clamp the stock preparatory to inserting a fastening therein.
- 25 10. In a machine for inserting metallic fastenings, a work-support, a vertically movable head, a rotating spindle carried by said head, mechanism actuated by said spindle to raise the head periodically to allow the work to be fed, and means to render said mechanism inoperative while the spindle continues to rotate.
- 30 11. In a machine for inserting metallic fastenings, a work-support, a vertically movable head, a rotating spindle, and mechanism actuated by said spindle to raise the head and maintain it in raised position without stopping the spindle.
- 35 12. In a machine for inserting metallic fastenings, a work-support, a head, a rotating spindle, mechanism actuated by said spindle for raising the head and maintaining it in raised position without stopping the spindle, and for lowering the head when fastenings are again to be inserted.
- 40 13. In a machine for inserting fastenings, a constantly-rotating wire-carrying spindle, connected wire-feeding means, an actuator for moving said wire-feeding means, and means intermediate said spindle and actuator to stop said actuator and the wire-feeding means when in predetermined position while the spindle continues to rotate.
- 45 14. In a machine for inserting fastenings, wire-feeding means, a rotary actuator for moving the same to feed wire, a constantly-rotating member rotatable about the same
- axis as the actuator; and means intermediate 65 said constantly-rotating member and the actuator to stop the latter and wire-feeding means when in predetermined position while said constantly-rotating member continues in its rotation.
- 50 15. In a machine for inserting fastenings, a stock support, stock-feeding means, an actuator therefor, a constantly-moving member, a driving member constituting part of the operating mechanism of the machine, 75 said moving member being connected to said driving member for actuation thereby, operative connections intermediate said actuator and moving member, and means controlling the operation of said connections for stopping 80 the actuator and the stock-feeding means when in a predetermined position while the moving member continues in operation.
- 55 16. In a machine for inserting fastenings, 85 the combination with fastening-inserting mechanism comprising fastening - feeding means and a driving member, operating mechanism for said feeding means comprising a constantly moving member driven by 90 said driving member, an actuator, and operative connections between said actuator and moving member, of means controlling the operation of said connections for stopping the actuator and feeding means when in pre- 95 determined position while the moving member continues in operation.
- 60 17. A machine for inserting fastenings comprising in part, a source of power, a constantly-moving member driven from said 100 source of power, said member constituting a portion of the train of operating mechanism of the machine, fastening feeding means, an actuator therefor, and means intermediate said moving member and actuator to stop 105 said actuator and feeding means when in predetermined position while the moving member continues in operation.
- 65 18. In a machine for inserting fastenings, the combination with a main driving mem- 110 ber driven from a source of power, an intermediate driving member driven from said main driving member, said intermediate driving member constituting a part of the operating mechanism of the machine, of fas- 115 tening-feeding means actuated from said intermediate driving member and means for interrupting the actuation of said feeding means when in predetermined position without interrupting the actuation of the inter- 120 mediate driving member.
- 70 19. In a machine for inserting fastenings, the combination with a main driving mem- 125 ber driven from a source of power, an intermediate driving member driven from said main driving member, said intermediate driving member constituting a part of the operating mechanism of the machine, of fas-

tenting-feeding and work-feeding means actuated from said intermediate driving member and means for interrupting the actuation of said two last-named means when in predetermined position without interrupting the actuation of the intermediate driving member.

In testimony whereof, I have signed my name to this specification, in the presence of two subscribing witnesses:

LOUIS A. CASGRAIN.
